CARRIER FOR A PORTABLE RADIO OR THE LIKE

Chester L. Holder, Hacienda Heights, Calif., assignor of one-half to T. Wayne Mathias, Alhambra, Calif.

Filed July 13, 1964, Ser. No. 80,818

Term of patent 14 years

(Cl. D3—10)

FIG. 1 is a front perspective view of a carrier for a portable radio showing my new design;

FIG. 2 is a rear view thereof;

FIGS. 3, 4, and 5 are respectively, front, side and top views thereof; and

FIG. 6 is a fragmentary sectional view taken on the line 6—6 of FIG. 1.

I claim:

The ornamental design for a carrier for a portable radio or the like, substantially as shown.
